(57) **CLAIM**

The ornamental design for a portion of a cushion clip for a respiratory mask, as shown and described.

DESCRIPTION

FIG. 1 is a front perspective view of a portion of a cushion clip for a respiratory mask according to our design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a rear perspective view thereof.

Where included, broken lines showing environment or structure are for illustrative purposes only and form no part of the claimed design. Where included, dotted lines represent the border between claimed and unclaimed subject matter and form no part of the claimed design.
